ORNAMENTAL WHEEL DISK

George Albert Lyon, Allenhurst, N. J.

Original application March 30, 1935, Serial No. 13,814. Divided and this application December 13, 1935, Serial No. 54,162. Renewed November 9, 1938

6 Claims. (Cl. 301—37)

This invention relates to an ornamental wheel disk, and more particularly to a wheel disk adapted to be snapped into engagement with retaining springs on a wheel of an automobile.

The subject matter of the present application has been divided from my copending application Serial No. 13,814, filed March 30, 1935, entitled "Method of and apparatus for die-forming parts".

10 An object of this invention is to provide an improved wheel disk for disposition over an outer side of a wheel such as an automobile wheel.

Another object of this invention is to provide a wheel disk having an inwardly deflected annular flange for use in the retention of the disk on the wheel.

15 Another object of this invention relates to the provision of an annular inwardly deflected part on a disk for retaining a skirt or sleeve on the interior of the disk.

20 In accordance with the general features of this invention, there is provided an annular disk having a central crown portion for disposition over the hub of the wheel and an outer peripheral portion for cooperation with an outer part of the wheel, the crown portion of the disk terminating in an annular inwardly deflected portion to provide the disk with a gooseneck.

Still another feature of the invention relates 25 to the employment of this deflected portion for securing and holding in place on the interior of the disk an annular flange or skirt.

Other objects and features of this invention will more fully appear from the following detailed description taken in connection with the accompanying drawing, which illustrates a single embodiment thereof, and in which:

Figure 1 is a front view of a disk embodying the features of this invention;

40 Figure 2 is an enlarged cross-sectional view taken on the line II—II of Figure 1 looking in the direction indicated by the arrows, and showing the skirt retained in position on the interior of the disk; and

45 Figure 3 is a sectional view somewhat similar to Figure 2, but differing from Figure 2 in that it shows the condition of the crown portion of the disk prior to its being deflected inwardly, and also shows the position of the skirt in dotted lines.

50 On the drawing:

The reference character 10 designates generally a disk embodying the features of this invention which may be made from any suitable material, such for example as metallic sheet.

The final form of the disk is shown in Figures 1 and 2, with an annular skirt or sleeve 11 secured in position on the interior of the disk. This disk may be manufactured on any suitable apparatus, but is preferably formed in accordance with the teaching in my aforesaid copending application.

5 The disk includes a central or crown portion 12 for disposition over a hub of a wheel, and a peripheral flange 13 for cooperation with an outer part of a wheel, such, for example, as the tire rim. The crown portion 12 is connected to the outer portion 13 by an intermediate convex portion 14.

The disk of my invention, like a hub cap, is 15 adapted to be snapped into retained engagement on the outer side of a wheel so as to conceal the wheel fastening bolts. Any suitable means may be employed to hold the disk in place, such, for example, as circumferentially spaced retaining 20 springs secured to the hub part of the wheel.

Now, in order to strengthen the disk at its place of securement to the wheel, as well as in order to provide a means by which it may be engaged and retained on the wheel, I have deflected the outer margin of the crown portion 12 from the position shown in Figure 3 to an inturned position such as shown in Figure 2. The condition of this portion of the disk prior to its being deflected is shown in Figure 3. It 25 will be noted that this portion 15 has a slight concave curvature, so that upon its being subjected to endwise pressure, as disclosed in my copending application, it will be deflected inwardly to provide an annular inwardly extending rib or flange 16 (Figure 2). This inturned flange 16 provides the disk with a gooseneck appearance between the crown and concave portions 12 and 14, in addition to providing the disk with an interior rib or flange by means of which the disk may be secured in place on the 30 wheel.

In reality, the deflecting of the portion 15 results in the crown portion 12 terminating in a reentrant groove 17 located between the portions 12 and 14. This groove, if it is so desired, may 35 be engaged by any suitable pry-off tool for forcibly prying the disk loose from the retaining means on the wheel.

In order further to rigidify and strengthen the 40 disk at its place of securement to the wheel, I contemplate that the interior of the crown portion 12 of the disk may be provided with an annular flange or sleeve 11 which is illustrated in dotted lines in Figure 3. In other words, in Fig- 45

ure 3 I have illustrated the position of this sleeve or flange 11 prior to its being secured to the disk by the clinching of the portion 15 thereto. When the portion 15 is clinched thereto, the inwardly extending annular flange 16 tightly embraces the inclined outer surface of the sleeve 11, as shown in Figure 2.

5 The flange 11 may be provided with a turned inner edge 18 over which the retaining means or 10 springs of the wheel are adapted to ride.

Now, I desire it understood that while I have 15 illustrated and described in detail a preferred form of my invention, the invention is not to be thus limited, but only in so far as defined by the 20 scope and spirit of the appended claims.

I claim as my invention:

1. An ornamental wheel disk provided with a central crown portion, an outer curved marginal portion and an intermediate conical portion, said 20 conical portion forming an annular reentrant groove for enhancing the appearance of the disk and for providing the disk with a rearwardly projecting concealed annular flange, said flange being clinched to an interiorly disposed circular 25 skirt projecting rearwardly from the crown portion of the disk, said skirt being arranged to engage disk retaining means on a wheel.

2. An ornamental wheel disk provided with a central crown portion and an outer curved marginal portion for cooperation with the outer side 30 of a wheel, said crown portion having disposed on the interior thereof a skirt clinched to the crown portion by the forming of a groove in the crown portion.

3. An ornamental wheel disk formed for cooperation with the outer side of a wheel and for disposition over the outer side of the wheel, having a central bulged crown portion and an interiorly disposed skirt secured to said disk solely

by the clinching of an intermediate portion of said disk thereon.

4. An ornamental wheel disk formed for co-operation with the outer side of a wheel and for disposition over the outer side of the wheel, having a central bulged crown portion and an interiorly disposed skirt secured to said disk solely by the clinching of an intermediate portion of said disk thereon, the clinched connection between the disk and said skirt providing the disk 10 with an intermediate annular reentrant groove.

5. An ornamental wheel disk provided with a central crown portion and an outer curved marginal portion and an intermediate relatively deep 15 annular reentrant groove for enhancing the appearance of the disk and for providing the disk with a rearwardly projecting concealed annular flange adapted to be engaged by disk retaining means on a wheel, said flange comprising a gooseneck portion radially inward of the outer margin 20 of said crown portion, and a circular skirt secured to said disk by said gooseneck portion.

6. An ornamental wheel disk provided with a central crown portion, an outer curved marginal portion and an intermediate relatively deep 25 annular reentrant groove for enhancing the appearance of the disk and for providing the disk with a rearwardly projecting concealed annular flange, said flange extending axially and radially inward between the outer edge of the crown portion and inner edge of said outer portion, said marginal portion extending a substantial distance beyond said groove for covering the outer side of the wheel adjacent the wheel rim, said flange having nested in and secured thereto a 30 rearwardly projecting circular skirt adapted to be engaged by disk retaining means on a wheel.

GEORGE ALBERT LYON.

CERTIFICATE OF CORRECTION.

Patent No. 2,148,210.

February 21, 1939.

GEORGE ALBERT LYON.

It is hereby certified that error appears in the above numbered patent requiring correction as follows: The present drawing should be canceled and the drawing containing three figures as shown below should be substituted therefor as a part of the Letters Patent -
